UNITED STATES PATENT OFFICE.

CLAUDE A. LEWIS, OF HOUSTON, TEXAS.

THEATER SEAT.

Application filed January 31, 1928. Serial No. 250,766.

My invention relates to seats such as are employed in theaters, show houses, raised platforms in restaurants, and the like. It is adapted for use particularly in the balconies 5 of show houses, although, as will be obvious, it is adapted for other similar uses. The seat is adapted for use particularly with the type of theater structure disclosed in my co-pending application for patent, Serial No. 240,802, 10 filed December 17th, 1927.

In this type of theater, the number of balconies is greatly increased but the width of each separate balcony is sufficient only for one or two seats between the aisle and the rail of 15 the balcony.

It is an object of this invention to provide a seat adapted to accommodate two people which is so arranged as to place both occupants of the seat in a position where they will 20 have a clear and unobstructed view of the stage. It is also desired to provide a small table or armrest in front of the occupants of the seat upon which objects may be placed or which may serve as a table upon which refreshments may be served. It is desired to so 25 construct the seat that the occupants may easily seat themselves in proper position therein, so that they may easily look over the rail at the inner side of the seat, and to provide 30 against any danger of accidental falling of the occupant over the rail of the balcony. It is also an object to economize space as far as possible but to still allow sufficient room for the comfort of the users of the seats.

Referring to the drawing herewith, Fig. 1 35 is a side view of the seats, said view taken approximately on the line 1—1 of Fig. 2. Fig. 2 is a top plan view of the seats and the rail taken on the line 2—2 of Fig. 3. Fig. 3 is a 40 vertical section through a plurality of balconies, showing the arrangements of the seats therein, said view being taken on the plane 3—3 of Fig. 2. Like numerals of reference are employed to designate like parts in all 45 the views.

In the type of theater structure disclosed in my co-pending application, previously referred to, the balcony arrangement involves the use of narrow balconies with an aisle 50 adjacent thereto, the seats on each balcony being placed below the balcony above, as will be noted from Fig. 3. The balcony 1, as shown in this figure, comprises an inner side wall 2 with an outer rail 3. Adjacent the inner wall 2 is an aisle indicated at 4 which is 55 of sufficient height to allow a patron to walk

upright with comfort. Between the aisle and the rail 3 are placed the seats 5. The balcony 1' above the balcony 1 extends inwardly over the seat 5 and to the outer boundary of the aisle 2. This arrangement is such that when a party is seated in the seat 5, there is plenty of clearance above his head beneath the balcony 1'. It is, however, necessary to move to the end of the seat adjacent the aisle 60 to rise to full height in moving to and from the seat.

The arrangement of the seats, which constitutes the principal feature of my invention, involves the forming of the seats on a line inclined forwardly from the rail. The back of the seat 6 is curved from the rail 3 forwardly so as to place the occupants of the seat in a position looking toward the stage. The bench portion 7 of the seat is of sufficient 70 width to provide a comfortable support, the end of the seat adjacent the aisle having an outer side 8 which is parallel with the aisle, the forward end 9 being extended on a line approximately perpendicular to the aisle and the seat is then rounded inwardly at 75 10 to provide clearance between the forward end 10 and the rear 11 of the seat in front. This gives sufficient clearance for the theater patron to seat himself upon the supporting 80 portion 7 facing toward the aisle and to then move around into the desired position in the seat in an obvious manner. The forward side of the seat 12 is rounded to conform to the curvature of the back 6 of the seat, leaving a 85 somewhat triangular space between the forward side of the seat and the rear of the adjacent forward seat.

The triangular space in front of the seat and adjacent the rail may be used to provide 90 a table or shelf 13. This table, as shown in Fig. 3, is set within the inner portion of the rail at 14, and also in a similar position beneath the upper rail of the seat in front. This will provide a substantial support for the 95 table and it is contemplated that the edge of the table will overlie the forward edge of the seat by a small margin, as indicated in Fig. 2. The table or shelf 13 serves the additional 100 purpose of bracing the back member of the seat to the rail and is thus substantially a part of the seat. Electric push buttons 15 on the rail adjacent the table may be provided to call the waiter when refreshments of any kind 105 are desired.

Each bench or seat is supported from beneath by a forward upright leg 17 and a rear-

ward post or support 18. These supports will be inwardly away from the aisle and will not interfere with the seating of the patron as he moves into the seat toward the rail and adjacent the table.

As previously stated, this structure is devised particularly to provide a seat for two persons adjacent the rail of the balcony wherein they may both be seated comfortably and have a view over the rail of the balcony directly toward the stage so that their view will not be obstructed by parties in the seats in front of them, or above them. It will be obvious that with the seats inclined forwardly 15 in the manner shown, relative to the rail, there will be sufficient room for two persons without crowding. The use of the table 13 in the forward angle of the seat will have the effect of a support upon which the patron may rest 20 his elbows and assume a comfortable position looking over the rail and directly at the stage. In assuming such a position he is enabled to see past the occupants of the seat in front of him and interferes in no way with 25 the view of the occupants of the seat behind him. The party adjacent the rail may have a view directly over the rail and will be enabled to lean slightly toward the rail so as not to obstruct the view of the other occupant of the seat.

With the construction of the seats in the balcony arrangement here shown, each patron of the show will be enabled to have what is substantially a box seat with a clear 35 view of the stage at an angle which enables him to place himself comfortably in his seat and enjoy the show. He is also enabled to move to or out of his seat into the aisle and to other parts of the house without interfering 40 with the occupants of other seats. There is the further advantage that the arrangements of the seats adjacent the aisle enables the occupant of the seat to receive refreshments at any time without interfering with the occupants of the adjacent seats and the 45 supporting table 13 provides a support for the refreshments being served, and also serves to prevent any likelihood of the falling of the patron over the rail as might otherwise occur. The further advantages of this arrangement will be apparent to those skilled in the art.

While I have shown and described a seat rather substantially made, it is the general 55 shape and relation of the seats to one another and to the rail that constitutes an important feature of novelty. I do not wish therefore to be limited to the exact form of the seat shown further than comes within the scope 60 of the claims herewith, it being clear that the structure may be varied somewhat without departing from the spirit of the invention.

What I claim as new is:

1. In a theater or the like, a balcony including a side rail, an aisle, a row of seats between said rail and said aisle, each seat being connected with said rail and curved forwardly to said aisle and of sufficient length to accommodate two persons. 65

2. In a theater or the like, a balcony including a side rail, an aisle, a row of seats between said rail and said aisle, each seat being connected with said rail curved forwardly to said aisle and of sufficient length to accommodate two persons, and a supporting table 70 mounted upon said rail and the rearward side of the seat. 75

3. In a theater or the like, a balcony including a side rail, an aisle, a row of seats between said rail and said aisle, each seat being connected with said rail, curved forwardly to said aisle, and of sufficient length to accommodate two persons, and an approximately triangular supporting table mounted 80 upon said rail and said seat. 85

4. A seat of the character described including a side rail, a row of seats along said rail, each seat being of sufficient width to accommodate two persons, said seats being supported at one end upon said rail, the seats 90 being curved forwardly to cause the occupants to face toward said rail at an acute angle thereto.

5. A seat of the character described including a side rail, a row of seats along said rail, each seat being of sufficient width to accommodate two persons, said seats being supported at one end upon said rail, the seats being curved forwardly to cause the occupants to face toward said rail at an acute angle 95 100 thereto, a back to each seat extending short of the outer end thereof to allow space on each seat for the user to sit before moving into forwardly facing position in said seat.

6. A seat of the character described including a side rail, a row of seats along said rail, each seat being of sufficient width to accommodate two persons, said seats being supported at one end upon said rail, the seats being curved forwardly to cause the occupants 105 110 to face toward said rail at an acute angle thereto, and a supporting table attaching each seat on said rail.

7. A seat of the character described including a side rail, a row of seats along said rail, each seat being of sufficient width to accommodate two persons, said seats being supported at one end upon said rail, the seats being curved forwardly to cause the occupants to face toward said rail at an acute angle 115 120 thereto, and means in back of each seat acting to protect the occupants of the rearward seat from falling over said rail.

In testimony whereof I hereunto affix my signature this 28 day of January, A. D. 1928. 125

CLAUDE A. LEWIS.
